CERAMIC WALL TILE

Patrick Boris Hopkins, Smithfield, New South Wales, Australia, assignor to Pilkington's Tiles Limited, Swinton, England

Filed Nov. 9, 1970, Ser. No. 25,887

Claims priority, application Great Britain Sept. 23, 1970

Term of patent 7 years

Int. Cl. D25—01

U.S. Cl. D18—2

FIG. 1

FIG. 1 is a top plan view of a ceramic wall tile embodying the design of the invention, the bottom plan being non-ornamental; and

FIG. 2 is a side elevation of the tile.

I claim:

The ornamental design for a ceramic wall tile, substantially as shown and described.
